PLATE GRINDING MACHINE

Stephan P. Mermer, Toledo, Ohio, assignor to The Commercial Savings Bank & Trust Company, Toledo, Ohio, a corporation of Ohio, as trustee

Application November 22, 1930
Serial No. 497,396

11 Claims. (Cl. 51—96)

This invention relates to the grinding of plates, but more particularly to grinding the edges of plates, as for example, glass plates used for windows and wind shields of vehicles.

5 An object of this invention is to provide a new and improved machine for automatically grinding or beveling the side and end edges of glass plates whereby at least one side edge and the adjacent end corners may be ground in the desired manner by movement of the plates in one direction, other edges being ground by changing the position of the plates with respect to the grinding device without removing the plates from the support.

15 Another object is to provide a simple and efficient machine which is operable successively to grind different edges of a glass plate without removing the plate from its support.

A further object is to provide a machine for 20 grinding one or more glass plates so constructed and arranged that a single grinding device may grind several side and end edges without the necessity of bodily removing the plate from its support.

25 A still further object is to provide a machine for grinding several edges of one or more plates or panels without removing the plates from the machine.

A still further object is to provide a machine for successively grinding or beveling an end edge, 30 a side edge, and then the opposite end edge of a plate or panel.

Further objects and advantages of the invention will hereinafter appear, and the invention is shown by way of illustration on the accompanying drawings, in which:

35 Fig. 1 is a side elevation of a machine for grinding or beveling the side edges and end corners of glass plates in which the plates are movable with respect to a grinding wheel on one side only of the wheel; and

40 Fig. 2 is a side elevation of an alternate form of machine for grinding glass plates in which the plates are moved partially around the grinding wheel, thereby to grind three side edges of the adjacent end corners of the glass plates.

The illustrated embodiment of the invention, as 45 shown in Fig. 1, comprises a frame 10, on which is mounted a grinding wheel 11. The wheel 11 is driven by an electric motor 12, which is connected by a belt 13 to drive a shaft 14 carrying a gear 15. The gear 15 meshes with a gear 16 movable with the grinding wheel 11.

50 Glass plates P are mounted on a carrier 17, which is adapted to support a plurality of plates.

The plates are held in vertically disposed position by a holder 18, which has a pivoted yoke 19. The yoke 19 is adapted to engage the rear edges of the plates away from the grinding wheel 11 for holding the same in alignment and in engagement with the grinding wheel. A form of plate carrier is shown in my Patent No. 1,687,985, and detail description thereof is not considered necessary in this instance. Suffice it to say that the carrier 17 is constructed in two sections pivotally connected at 20 so that one section may swing relatively to the other. This enables the plates P to be moved in order to rest on their forward edge f, a suitable latch 21 being adapted to engage a pin 22, which is adapted to hold the carrier 60 sections at right angles to each other until the holder 18 has been moved to the desired position to hold the plates in proper position.

The carrier 17 is supported by rollers 23, which rest on a platform 24. A coil spring 25 urges the 70 carrier 17 toward the grinding wheel 11. One end of the spring 25 may be detachably connected in order that it may be released for a purpose hereinafter described. The platform is swiveled at 26 to a mounting 27. This enables the platform 24 to be swung around in order to present the opposite edges of the plates P to the grinding wheel 11. For example, after the side edge f and adjacent corners have been ground the platform 24 may be swung around through an angle of 180° 75 to present the edges g to the grinding wheel 11. At such time the yoke 19 is swung to the dotted line position to hold the opposite edges in desired alignment.

80 From the above it is apparent that the glass plates P are carried by a universal support which is adapted to present one edge of the plates P to the grinding wheel 11, and then by swinging the mounting through an angle of 180° the opposite edges are presented to the grinding wheel. 85 Thereafter, if the remaining edges are to be ground the sections of the carrier 17 may be swung relatively to each other in order to swing the plates through an angle of 90°, whereupon first one edge and then the opposite edge may be presented to 90 the grinding wheel. In order yieldingly to urge the carrier 17 toward the grinding wheel 11 when the carrier is swung around from the position shown on Fig. 1, a spring 25a is connected to the forward portion of the carrier. It will be obvious 95 that the spring 25 must be detached and the spring 25a connected for this purpose.

100 The mounting 27 is supported by bell crank levers 28 and 29 of substantially triangular shape. The bell cranks 28 and 29 are pivoted at 30 and 110

31 respectively to the frame 10. As shown, a link 32 pivotally connects the lower end portions of the bell cranks 28 and 29. An arm 33 is pivotally connected to the lower end portion of the bell 5 crank 29 and the outer portion of a worm wheel 34. A worm 35 drives the worm wheel 34, and a motor 36 is connected to drive the worm 35.

In operation, it will be understood that the mounting 27 is reciprocated by the bell cranks 10 29, which are actuated by the worm wheel 34 through the connections above described. Since the plates P are yieldingly urged toward the grinding wheel 11, it will be apparent that, during movement in one direction, end corners, side 15 edges, and the opposite end corners of the plates are successively ground. The plates P tend to follow the periphery of the grinding wheel 11, so that during the start of the movement of the plates in one direction, end edges in engagement with 20 the grinding wheel 11 are ground as they pass over the grinding wheel; subsequently, the side edges are moved into engagement with the wheel, and finally the opposite end edges of the plates following for a portion of their travel the periphery of the grinding wheel, operate to grind or bevel the same. After one side has been ground the platform 24 may be swung around and then the opposite side may be similarly treated. If the 25 remaining side edges are to be ground the sections of the carrier 17 may be adjusted after the manner above described.

From the above description it is manifest that the machine is operable successively to grind or bevel an end edge, a side edge, and thereafter the 30 opposite end or corner edge without manual handling of the plate. Not only is it possible to grind a single plate in this manner, but a considerable number of plates may be simultaneously ground. In such event it is necessary that a relatively long 35 grinding wheel be provided, and, preferably, the wheel is grooved circumferentially in order to obtain the desired bevel of the glass plates. Grooved grinding wheels of this character are well known to those skilled in this art. Since the four side 40 edges and adjacent corners of a plurality of glass plates may be ground without removing the plates from the support, it is manifest that breakage of the plates, due to the handling thereof, is practically eliminated, so that not only does this machine facilitate production, enabling a large number of plates to be ground in a comparatively short 45 period of time, but also dispenses with losses, which have heretofore been occasioned due to breakage or cracking of the plates in the handling of them.

In the form of my invention shown in Fig. 2, a single grinding wheel 11^a is provided mounted for rotation on a frame 10^a. Platforms 27^a and 27^b are disposed on opposite sides of the wheel 11^a. The platform 27^a is actuated by bell crank levers 37 and 38, which are similar to the bell cranks 28 and 29, and are pivoted to the frame 10^a. The lower ends of the bell cranks 37 and 38 are pivotally connected by a link 39. The link 60 39 is connected by an arm 40 to the outer portion of a worm wheel 41 deriving its power from a motor 42 through suitable gearing 43 and a worm 44. The mounting 27^b is similarly actuated by bell cranks 45 and 46, which are connected at 65 their lower ends by a link 47, which in turn is pivotally connected by an arm 48 to the worm wheel 41 at a point diametrically opposed to the connection between the arm 40 and the worm wheel.

70 A carrier 49 is supported on the mounting 27^a

by rollers 50, and a carrier 51 is supported on the mounting 27^b by rollers 52. The glass plates P' are adapted to be held in upright position on the carriers by a holder 18^a similar to the holder 18 above described.

In operation, the carriers 27^a and 27^b move up and down together with respect to the grinding wheel 11^a. Assuming that the glass plates P' are mounted on the carrier 49 and the platform 27^a is in its lowered position, upon upward movement of the platform 27^a it will be apparent that one side edge and adjacent end corners will be beveled in the manner heretofore described. The upward movement of the platform 27^a continues until the lower edges of the glass plates P' are substantially in alignment with the upper edge of the grinding wheel 11^a.

The plates P' are then moved horizontally over the grinding wheel 11^a in order to grind or bevel the lower side edge and adjacent end corners after the manner heretofore described. This movement is accomplished by means of an endless chain 53 supported by sprockets 54 mounted at opposite ends of the machine frame 10^a and driven in any suitable manner by a motor 55, 100 which may also be connected to drive the grinding wheel 11^a. It is apparent that on the carriers 49 and 51 are rollers 56, over which the plates P' may ride. An actuator 57 suitably guided on the carrier 49 is provided with a finger 105 58 adapted to engage in a link of the chain 53. A roller 59 carried by the actuator 57 is engageable with the plates P'.

It will be apparent that when the carrier 49 moves upwardly the finger 58 of the actuator 57 will be forced into engagement with one of the links of the chain 53, and thereupon the plates P', together with a holder 18^a, will be moved horizontally over the grinding wheel 11^a, thereby grinding the lower side edge and adjacent side 115 corners after the manner above described. It will be understood that during this movement the plates P' may or may not rest upon and be supported by the grinding wheel 11^a depending upon the space between the carriers 49 and 51 when in 120 raised position and the size of the plates P'.

Horizontal movement of the plates P' continues until the rear end corner is beveled, and the plates are disposed upon the carrier 51 which, during the horizontal movement of the plates, 125 has moved downwardly and is again brought upwardly in position to receive the plates P' and holder 18^a. Thereupon the platform 27^b, which supports the carrier 51, is moved downwardly so that the rear side edge and adjacent end corners is beveled. It will be understood that the actuator 57 is disengaged from the chain 53 and returned to the carrier 49. After the carrier 51 has moved to its lowermost position and the three side edges and their corners have been ground, 130 the plates may be manually discharged from the machine.

From the above description it is manifest that the plates P' are first moved upwardly at one side 140 of the grinding wheel 11^a, then horizontally across the top of the grinding wheel, and finally downwardly, thereby grinding successively three side edges of the plates. In the form shown, a somewhat curvilinear motion is imparted to the plates during their upward and downward movements, whereby the four end corners of the plates are beveled or ground so that not only are the side edges of the plates ground, but the adjacent end corners as well, in a substantially continuous 145 150

operation without the necessity of handling or careful attention.

It is to be understood that in the forms of my invention shown in Figures 1 and 2, the side edges 5 of the plates may be ground without grinding the end corners, this being effected by imparting more nearly rectilinear movements to the plates instead of curvilinear movements. Under some conditions it may not be necessary to grind the end 10 corners, and yet grinding or beveling of the side edges be quite desirable. Should it be found desirable to grind a side edge and but one end corner, this may be accomplished by starting a plate at approximately the central portion of one side 15 of the grinding wheel.

Numerous changes in details of construction, arrangement and operation may be effected without departing from the spirit of the invention, especially as defined in the appended claims. Although I have described the construction and operation of the embodiments of the invention in respect of glass plates, it is within the purview of the invention to similarly grind plates of materials other than glass.

25 What I claim as new and desire to secure by Letters Patent is:

1. The combination of a grinding device, a carrier for supporting a plate in substantially vertical position, means to hold the plate in engagement with said grinding device, means to impart relative shifting movement between said carrier and grinding device thereby to grind one side of the plate, and a swivel mounting for said carrier whereby said carrier may be swung around to 35 grind an opposite side of the plate.

2. The combination of a grinding wheel, a pair of plate-supporting carriers disposed respectively on opposite sides of said grinding wheel, a means to impart reciprocatory movements to said carriers in parallel planes at substantially right angles to the axis of said wheel, a holder for said carriers for retaining the plate in substantially vertical position and in edge engagement with said wheel, and means to shift said holder across 45 said wheel from one carrier to the other.

3. The combination of a grinding wheel, a platform reciprocable vertically at one side of said wheel, means to impart movement to said platform, a carrier for supporting a plate on edge 50 in substantially vertical position and in edge engagement with said wheel, and means for mounting said carrier on said platform to enable horizontal movement of said carrier with respect to said platform.

55 4. The combination of a grinding wheel, a platform reciprocable vertically at one side of said wheel, means to impart movement to said platform, a carrier for supporting a plate on edge in substantially vertical position and in edge engagement with said wheel, means for mounting said carrier on said platform to enable horizontal movement of said carrier with respect to said platform, and a swivel mounting for said platform to enable the latter to be swung about to 60 present an opposite side to said grinding wheel.

65 5. The combination of a grinding wheel, a platform vertically reciprocable at one side of said wheel, means to impart movement to said platform, a carrier for supporting a plate on edge in

substantially vertical position and in edge engagement with said wheel, said carrier being so constructed as to tilt the plate thereon from one side to another, and means for mounting said carrier on said platform to enable horizontal movement of said carrier with respect to said platform.

6. Glass plate grinding apparatus comprising a glass plate carrier, a grinder for grinding the side edges and end corners of the plate, means to impart to and fro movements to said carrier on one side of said grinder thereby successively to grind an end corner, a side edge and opposite end corner, and means to adjust said carrier for selectively positioning other edges and corners of the plate for grinding without removing the plate from the carrier.

7. Glass plate grinding apparatus comprising a glass plate carrier, a curvilinear grinder, means to impart movement to said carrier relative to said grinder for causing the plate to travel in a curvilinear path with an edge thereof in engagement with the grinder thereby to grind opposite end corners and a side edge of the plate, and means to shift said carrier for presenting other edges of the plate to said grinder without removing the plate from said carrier.

8. Glass plate grinding apparatus comprising a rotatable grinder, a glass plate carrier adapted to hold an edge of the plate in engagement with said grinder, and means to move said carrier in one plane for grinding a side edge of the plate and then to shift said carrier into another plane to grind another side edge, and then to shift said carrier into a plane parallel to the first plane 110 for grinding a third edge.

9. The combination of a grinding wheel, a platform reciprocable at one side of said wheel during the grinding operation, means to impart vertical movement to said platform, a carrier 115 on said platform for supporting a plate with the plane of the faces thereof disposed at substantially right angles to the axis of said wheel, means to adjust said carrier to tilt the plate thereon from one side to another, thereby to 120 present another side to said wheel, and means for mounting said carrier on said platform to afford lateral movement thereof toward and away from said wheel.

10. Glass plate grinding apparatus comprising circular grinding means, a carrier for a substantially rectangular glass plate, means to hold the plate against rotative movements during the grinding operation, means to effect translatory movement between said carrier and grinding 130 means with an edge of the plate in engagement with the grinder to cause the plate to follow the curvature of said grinding means.

11. In a glass plate grinding apparatus, means to support a plate of glass on edge and in upright position, a circular grinder for grinding the edge of said plate, and means to impart translatory movement to said supporting means in a path defined by the periphery of said grinder and in such manner that the plate is maintained with its edge portions in the same relative position throughout its movement.
